CLOSURE OPERATOR

Charles E. Abbe and William O. Ward, Flint,
Mich.

Application August 13, 1936, Serial No. 95,923

1 Claim. (Cl. 268—35)

This invention appertains to new and useful improvements in means for operating closures, and more particularly to closures such as garage doors and the like.

5 The principal object of the present invention is to provide a garage door operator which can be automatically operated by a vehicle approaching the garage or in the act of leaving the garage.

Another important object of the invention is to 10 provide a closure operator of the character described which will be substantially fool-proof in operation.

Another important object of the invention is to 15 provide a closure operator of the character stated which will, because of its simple construction not be susceptible to the ready development of defects.

These and various other important objects and 20 advantages of the invention will become apparent to the reader.

In the drawings:

Figure 1 represents a horizontal sectional view through the front portion of the garage showing the doors in closed position.

25 Figure 2 represents a fragmentary vertical sectional view through the forward portion of a garage showing the doors in closed position and also by dotted lines in open position.

Figure 3 is a fragmentary vertical sectional 30 view taken substantially on line 3—3 of Figure 1, looking forwardly.

Referring to the drawings wherein like numerals designate like parts, it can be seen that the garage is generally referred to by numeral 5 35 and consists of the side walls 6—6 and the roof 7. Numeral 8 represents the foundation for the garage which extends forwardly of the front of the garage. A substantial portion of the foundation extending from a forward point of the 40 garage and into the garage is provided with the depression 9. Numerals 10—11 represent the outside and inside treadle platforms which are hingedly connected as at 12 to the slide board 13 which is vertically slidable in the guide trough 45 14 formed in the foundation 8.

Numerals 15—16 generally refer to the two doors which are hingedly connected as at 17—17 to the vertical members 18—18 of the door frame 50 and each of these doors is made up of a pair of sections a—b hingedly connected together as at c.

The free ends of the treadle plates 10—11 are 55 provided with rollers 19 on their under side for riding engagement against the bottom of the depression 9.

At the forward end of each side wall 6 is a balancing unit generally referred to by numeral 20 (see Figure 2). A description of one of these units will suffice for both. The unit consists of the casing 21 in the upper portion of which is 5 an inverted T-crank 22, the upstanding portion of which is connected to the clevis 23 of the arm 24 projecting inwardly from the section b of the corresponding doors 15—16.

A rod 25 extends upwardly from the inner platform 11 and connects by the turnbuckle 26 to one of the remaining arms of the T-crank 22, while the last of the arms of the T-crank 22 has a rod 27 depending therefrom and provided with a weight 28 at its lower end. Obviously, this 15 weight 28 serves to maintain the platforms 10—11 always in elevated position as shown in Figure 2, maintaining the doors closed.

For causing the sections a—b of each of the 20 doors 15—16 to operate coordinately, a link member 29 extends from each of the vertical frame members 18 to connect to the outer end of a rocker 30 located on the upper edge of the adjacent door section b, while the inner end of this rocker is connected to the adjacent section a by 25 a pivotal link 31. Thus, the door sections a—b will fold as they open.

Numeral 32 represents a casing which extends 30 horizontally and is secured to the upper portion of the door frame so as to encase the rocker 30 and links 31—29 as well as to act as an abutment for the door section.

As can be seen in Figure 2, numeral 33 represents a bumper for the platform 11 and a suitable locking means generally referred to by numeral 34 can be employed under the front platform 10. 35 This means 34 may consist of the push rod 35 operative through guides 36—36 and operating a bell crank 37 which in turn is connected to a bolt 38 operative through a keeper 39 provided on the bottom of the depression 9, so that the platform 10 can be depressed and the bolt 38 operated to pass through the keeper 39 so that the doors will remain in open or closed position. 40 45

It is also preferable that one of the door sections a be provided with a supplemental door d hingedly connected as at e to its companion section b. A suitable latch mechanism f can be 50 provided for this small door d.

While the foregoing specification sets forth the invention in specific terms, it is to be understood that numerous changes in the shape, size, and materials may be resorted to without depart- 55

ing from the spirit and scope of the invention as claimed hereinafter.

Having described the invention, what is claimed as new is:

- 5 A garage door closure comprising a depressible treadle platform, a base upon which the platform operates, a pair of swingable doors, operating means between the platform and the doors, whereby depression of the platform will cause the doors to swing to an open position, a slidable rod
- 10 having one end protruding beyond one side of

the platform, guide means under the platform through which the rod is slid able, a rockable bell crank to which one end of the rod is pivotally connected, and a keeper with which the opposite end of the bell crank is engageable when the platform is in depressed position for maintaining the said platform in depressed position and the doors in open position.

CHARLES E. ABBE.
